UNITED STATES PATENT OFFICE.

ASHLEY G. OGDEN, OF BALTIMORE, MARYLAND, ASSIGNOR TO AMERICAN MACHINE & FOUNDRY COMPANY, A CORPORATION OF NEW JERSEY.

PHOTOGRAPHIC-PRINTING DEVICE.

Application filed March 5, 1921. Serial No. 449,802.

To all whom it may concern:

Be it known that I, ASHLEY G. OGDEN, a citizen of the United States, and a resident of Baltimore, county of Baltimore, and State of Maryland, have invented certain new and useful Improvements in Photographic-Printing Devices, of which the following is a specification.

This invention relates to photographic devices and is hereinafter described as being adapted to be applied to machines of the general type shown in the patent to Ogden, Reissue No. 14,517, dated September 3, 1918, for photographically producing lithographic plates.

In such and other machines it is found desirable to have a shield corresponding to the ordinary plate-holder shields of photographic cameras to enable the sensitized surface to be carried around in its plate-holder without exposure to light. In many cases, however, such a shield must be relatively large and difficult to handle if it is to expose the whole plate or surface when withdrawn; and if made of many substances otherwise suitable, such as hard rubber, is brittle or likely to warp.

According to the present invention the shield may take the form of a flexible sheet which is adapted to run in suitable guides of the plate-holder and which may be withdrawn from the surface of the plate-holder into a shield-holder which may be temporarily held to or attached to the plate-holder. The shield-holder when detached from the plate-holder forms a convenient device for supporting the shield and for carrying it around, so that it will not be easily damaged. The shield has been found to be very satisfactory if made of an opaque fabric stiffened by suitable battens.

Other features and advantages will hereinafter appear.

In the accompanying drawing;

Figure 1 is a perspective view of a plate-holder with the shield-holder in shield-receiving position.

Figure 2 is a longitudinal sectional view of the device shown in Figure 1 with a shield inserted, the frame being omitted and the shield shown in end elevation partially retracted.

Figure 3 is a fragmental view of one form of shield.

The plate-holder having sides 2 and ends 3 with which is associated a back 4 is adapted, in accordance with present practice, to be seated in a cradle not shown to enable the same to be shifted horizontally and to be lifted or depressed. The back 4 is provided with a center opening 5 adjacent to which are formed ledges 6 which serve to limit the movement of a plate carrying mount of backing 7 normally supported by means of springs 8. These springs are permanently attached to the mount 7 and are supported by the back 4 upon which they so rest as to permit a relative slight movement of the mount when pressure is applied thereto in the carrying out of a printing operation as described in said Reissue Patent No. 14,517.

The mount carries a sensitized plate 7' which is cushioned with respect to the mount 7 by means of an interposed blanket 8' of yieldable material which may overlie the ledges 6 as shown at 6' for the purpose of excluding light which may otherwise enter between the mount 7 and adjacent portions of the back 4 through the opening 5.

For shielding the under face or sensitized surface of the plate 7' from the light there is provided a flexible shield 9 herein shown as comprising a piece of opaque cloth 10, preferably black, with closely set transverse stiffening battens 11 extending across it so that the ends of the battens and the cloth extend into rabbeted guides 12 in the back 4 and may slide therein. The guides 12 are curved upwardly at a point an appreciable distance from the plate 7' as shown at 13. The bend or curve 13 is sharp enough to shut out light which might otherwise enter, when the shield, which is of such a length that it always projects through said bend, is withdrawn from the plate-holder 1. When it is desired to remove the shield from the plate-holder, a supporting frame 14 comprising sides 15, an upper end 16 and a lower end 17, is held adjacent the bend 13 by means of pins, one of which is shown at 18, which project from a stiffening member 14' secured to the end 17, the pins 18 being adapted to enter holes, one of which is indicated by the numeral 19, formed in the back 4. With the

supporting frame 14 in this position the end of the shield 9 is adapted to project from openings or slots 20 and 20' formed in the end 17 and stiffening member 14' respectively, which slots register with each other and the end of the curve 13. This permits the operator to draw the shield 9 upward, the ends of the battens 11 and cloth 10 sliding along in guide rabbets 21 cut in the 10 sides 15.

When the shield 9 has been wholly withdrawn from the plate-holder 1 the supporting frame, above described, may be lifted and carried away, carrying with it the shield 9 15 now wholly supported therein, thus clearing the end or sensitized faces of the plate 7' of any obstruction which would interfere with the operation of machines of the class with which my invention is particularly adapted 20 to be used.

When it is desired to replace the shield in the plate-holder the supporting frame 14 is brought into the position shown in Figure 2 with the pins 18 resting in the holes 19 and 25 then the shield is slid into position by pushing downward upon its upper end so that it slides through the guides 21, the curve 13 and into the side guides 12 covering the plate with the result that the plate-holder 30 can be now removed without any danger of what is commonly known as "fogging" the plate.

Having thus described one embodiment of my invention, what I claim is:

1. In a photographic device, the combination 35 with a plate-holder provided with guides, and a shield stiffened to enable it to be slid into said guides in the plate-holder, and a removable supporting frame 40 adapted to fit upon the plate-holder to receive the shield therefrom and having guides into which the shield slides.

2. The combination with a plate-holder provided with guides having curved ends, 45 of a shield stiff enough to be thrust into said guides in the plate-holder, and yieldable to bend around curved ends of the guides, a shield-receiving frame having guides adapted to register with the curved ends of the plate-holder guides, so that the shield may be slid from the plate-holder into the receiving frame, and guide members adapted to hold the shield-receiving member in position upon the plate-holder to 55 cause the guides to register.

3. The combination with a plate-holder provided with pin receiving openings and with guides having curved ends, of a shield stiff enough to be thrust into said 60 guides in the plate-holder and yieldable to bend around curved ends of the guides, a shield-receiving frame having guides adapted to register with the curved ends of the plate-holder guides, so that the shield may 65 be slid from the plate-holder into the re-

ceiving frame, and pins upon the slide-receiving frame adapted to fit in openings on the plate-holder to bring the supporting frame guides into register with the plate-holder guides.

4. The combination with a plate-holder provided with guides having curved ends, of a shield for the plate-holder comprising a fabric base and battens adapted to stiffen it, and adapted to fit in said guides in the 75 plate-holder and to be slid out from the plate-holder by curved ends of the guides through the back of the plate-holder.

5. The combination with a plate-holder provided with guides having curved ends, 80 of a shield for the plate-holder comprising a fabric base and battens adapted to stiffen it, and adapted to fit in said guides in the plate-holder and to be slid out from the plate-holder by the curved ends of the guides 85 through the back of the plate-holder, and a shield-receiving device adapted to be fitted onto the back of the plate-holder to receive the shield and support it while it is removed from the plate-holder.

6. The combination with a plate-holder provided with shield support centering devices and with guides having curved ends, of a shield for the plate-holder comprising a fabric base and battens adapted to stiffen it, and adapted to fit in said guides in the plate-holder, and to be slid out from the plate-holder by the curved ends of the guides through the back of the plate-holder, and a shield support having guides to receive the shield and having devices adapted to fit in co-operating devices upon the plate-holder to center its guides relatively to the plate-holder guides.

7. In a photographic device a plate-holder provided with a guide, said guide being curved at one end thereof through said holder sharp enough to exclude light, a flexible shield adapted to be inserted into said guide and withdrawn therefrom through the curved end thereof, and a shield receiving device adapted to be positioned at the curved end of said guide to receive said shield and support the same as it is withdrawn from said guide.

8. In a photographic device a plate-holder provided with a guide, said guide being curved at one end thereof through said holder sharp enough to exclude light, a flexible shield in the form of a fabric element having battens set closely together across said element to stiffen the same, said shield being adapted to be inserted into said guides and withdrawn therefrom through the curved end thereof, and a shield receiving device adapted to be positioned at the curved end of said guide to receive said shield and support the same as it is withdrawn from said guide.

9. The combination with a plate-holder,

of a light shield movable to and from a position covering the plate, a support for said shield removably associated with said holder, and guide means for controlling the

5 movement of the shield in moving to and from said support and holder.

10. The combination with a plate-holder, of a supporting frame disposed at an angle to the plane of said plate-holder, an opaque shield for the plate adapted to be moved from said frame into said holder and from said holder into said frame, and means for guiding said shield in its movement into and out of said holder.

15 11. The combination with claim 10 with means for removably attaching said frame to the holder.

12. In a photographic device, the combination with a plate-holder, of a shield for 20 the plate, supporting frame for said shield projecting from the back of the plate-holder, and means for guiding the shield in its movement between its supporting frame and the plate-holder.

25 13. The combination with a plate-holder, of a shield for the plate, a supporting frame for the shield secured thereto and being exposed to the outside light, the plate-holder being opaque to prevent any outside light 30 from affecting said plate, and guide means

to direct the movement of the shield to and from the holder and frame, said guide means shielding the plate from any outside light.

14. The combination with a plate-holder, 35 of a shield for the plate, a supporting frame for the shield projecting from the plane of said plate-holder at an angle thereto, the supporting frame being exposed to the light while the plate-holder is opaque to protect 40 the sensitized plate, and guide means for facilitating the movement of the shield to and from said holder and frame without exposing the plate to the light.

15. In a photographic device the combination with a plate-holder, of a shield supporting frame removably secured to and projecting from said holder at an angle thereto, the supporting frame being exposed to light, the plate-holder being opaque to 50 protect the plate carried thereby, a shield for the plate adapted to be transferred from said support to said holder and vice versa, and means for guiding said shield in its movement to and from said holder and 55 frame.

In testimony whereof, I have affixed my signature to this specification.

ASHLEY G. OGDEN.
